BUCKING BAR CONTROL FOR RIVETING HAMMERS

Filed Dec. 1, 1942

UNITED STATES PATENT OFFICE

2,375,691

BUCKING BAR CONTROL FOR RIVETING HAMMERS

James A. Roberts, Detroit, Mich., assignor to
Chicago Pneumatic Tool Company, New York,
N. Y., a corporation of New Jersey

Application December 1, 1942, Serial No. 467,531

7 Claims. (Cl. 78—48)

This invention relates to riveting assemblies comprising a pneumatic hammer and a bucking bar cooperating to set a rivet. More particularly the invention is concerned with means placing the hammer action under the joint control of the operator holding the hammer and the holder of the bucking bar. The invention has especial, though not limited application to aircraft riveting tools, which operate on light sheet metal.

In the use of riveting assemblies of this kind the operators stand on opposite sides of the work, sometimes out of one another's view. In devices of prior design, the throttle valve is arranged to be under the control of a single operator, either the riveter or the bucker, who usually delays the start of the hammering operation until certain that the other operator is ready. Occasionally it happens that the hammer is started before the rivet is properly backed up, or before the hammer is placed in operative position, in either of which events the work may be damaged. The present invention obviates delays and prevents accidents by positively precluding starting of the hammer until the bucking bar is in position to absorb the blows thereof.

An object of the invention is to increase the speed and efficiency of the riveting assembly by making the compressed air supply subject to control both from the hammer and from the bucking bar.

A further object is to embody in the hammer a throttle valve under the control of the hammer operator, and an auxiliary valve in series with the throttle valve and controlled from the bucker.

Still another object of the invention is to connect the hammer and the bucking bar by a flexible Bowden type cable adapted to transmit the motion of manipulative means on the bucking bar to the auxiliary valve in the hammer.

A feature of the invention is that the auxiliary valve is contained in a fitting which together with the interconnecting Bowden cable may be mounted as an attachment on riveting hammers already in use.

Other objects and structural details of the invention will be apparent from the following description when read in conjunction with the accompanying drawing, wherein:

Fig. 1 is a view, partly in side elevation and partly in longitudinal section, of a riveting assembly comprising the invention; and

Fig. 2 is a view of the bucking bar in cross section, being taken substantially along the line 2—2 of Fig. 1.

Referring to the drawing, a riveting assembly in which the invention may be embodied comprises a pneumatic hammer 11 of a type finding particular favor in the aircraft industry where it is used to upset small aluminum alloy rivets. The hammer is made up of a cylinder 12 and an offset handle 13. The cylinder houses a motor including a reciprocable piston 14 and means for directing pressure fluid alternately to the ends thereof, while the handle is formed with an air inlet 15 and throttle means operating under the control of a trigger 16. The piston 14 acts as a hammer, delivering impacts to an anvil 17 which extends beyond the front end of the cylinder for engagement with the work. The work, in this instance, is represented by overlapping plates 18 and 19 which are fastened together by rivets to form part of an airplane skin covering. Guide holes in the work receive rivets, as the one indicated at 21, the rivets being disposed with preformed heads contacting the work on one side thereof and shank portions projecting from the opposite side. According to one method of riveting, the anvil 17 is pressed against the preformed head on the rivet while the shank portion is engaged on the opposite side of the work by a bucking bar 22. When the hammer is started percussive impulses are delivered to the work through the anvil 17 and are sustained by the bucking bar 22. Forward pressure being exerted by the bucking bar throughout the operation the reaction of the hammer blows serves to upset the shank of the rivet, a flat or curved head being thereby formed on the side of the work opposite the preformed head.

It is important that the skin surface be not marred or scratched by a premature hammer action. Therefore care must be exercised by the separate operators holding the hammer and the bucking bar that the ends of the rivet are properly engaged before the hammer is started. The present invention aims to guard against the misoperation resulting from a lack of such engagement by placing the compressed air supply under the joint control of both operators. Thus the piston 14 cannot begin its motion until the operators of the hammer and bucking bar signify by releasing the air supply that their respective implements are in working position.

The air inlet 15 is part of a pressure fluid supply passageway including passages 23 and 24 connected through a bore 25. Within the bore 25 is a bushing 26 having ports registering respectively with passages 23 and 24. Communication between passages 23 and 24 is controlled

by a valve 27 in bushing 26. The valve 27 is pressed by a spring 28 to a seat 29 between the ported areas of the bushing and so normally prevents the flow of fluid to the passage 24 and thereby to the hammer cylinder. The valve 27 has a stem extending upward through and beyond the bushing 26, the upper end of the stem underlying one arm of a lever 31. The lever 31 is pivotally mounted at 32 within a recess in the handle 13 and is engaged with the trigger 16. When the trigger is pulled rearward the lever 31, rocking upon its pivot 32, unseats the valve 27 whereupon air from inlet 15 and passage 23 is allowed to flow through the bushing 26 and into passage 24 where it is directed to the motor, thereby initiating operation of the hammer.

Heretofore, air has been supplied to the inlet 15 by a flexible hose line coupled directly thereto. According to this invention, however, there is placed between the inlet 15 and a hose line 33 a fitting in the form of an auxiliary valve housing 34. The housing 34 has a tubular portion 35 extending into the inlet 15 in threaded connection with a bushing 36. The body of housing 34 defines a chamber 37 receiving air from the hose line 33 and communicating with the interior of tubular portion 35 by way of a passage 38. Controlling the flow of air from chamber 37 to passage 38 is a valve 39, the head of which lies within the chamber 37 while a stem portion extends through the passage 38 and into a split projection 41 on the housing. The head of valve 39 is adapted to occupy a seat on the peripheral edge of passage 38 and so cut off the flow of fluid from chamber 37 to tubular portion 35 and inlet 15. Thus, the supply of air to the hammer is under the dual control of the throttle valve 27 and the auxiliary valve 39, either or both of which when closed will cut off the fluid flow and so prevent operation of the hammer. The valves 27 and 39 may be said to be arranged in series.

Opening of the valve 39 is accomplished by remote control from the bucking bar 22. Extending between the hammer and bucking bar is a flexible Bowden type cable 42 made up of a wound sheath 43 and an inner wire or core 44. At its one end the cable 42 is received in the split projection 41 of housing 34 and at its other end extends through a similar projection 45 on the bucking bar into a transverse bore 46 therein. Screws 47 and 48 in the respective split portions 41 and 45 provide a means of clamping the ends of the cable within the implements. The core 44 is movable longitudinally within the sheath 43 and is arranged with its opposite ends projecting beyond the sheath. One end of the core 44 is secured to the stem of valve 39, as by soldering or brazing, while the other end of the core extends outside the bore 46 and is fastened to a lever 49 by a set screw 51. The lever 49 is pivotally connected to the bucking bar by a cross pin 52 and serves as a manipulative means for actuating the Bowden cable. Upon depression of the lever 49 the core 44 acts as a plunger on valve 39 moving it to an unseated or open position and allowing the air to flow from chamber 37 to inlet 15. From there, if the throttle valve 27 is opened, the air may enter the motor supply passages and reciprocation of the hammer piston will begin. The valve 39, core 44 and actuating lever 49, being secured together, comprise an assembly and spring pressure may be applied at any point in the assembly to maintain the valve normally closed. In the present instance such pressure is 75

provided by a coil spring 53 surrounding the core 44 beneath the lever 49 and seated in a counterbore 54 in the bucking bar.

The cable 42 is of a length that it may be passed around the work or through an opening therein and allow freedom of movement of the respective tools at its ends. The bucking bar operator holds the lever 49 within his grasp, and, when the bar has been brought to bear against the shank 10 of the rivet, depresses the lever to open auxiliary valve 39. Then, when the throttle valve 27 in the hammer is opened, the assembly will begin the work of setting the rivet. Opening of the throttle valve 27 before the bucking bar is engaged with the rivet will not, as in the past, cause a misoperation of the assembly since the hammer remains inactive until the operator of the bucking bar signals his readiness by depression of the lever 49. Considering the lever 49 as a trigger, 20 both triggers 16 and 49 must be compressed before the hammer can drive the rivet. The efforts of the operators as a team are thereby synchronized, and the speed and efficiency of their work are increased.

25 What is claimed is:

1. A riveting assembly, comprising a fluid pressure operated hammer, a bucking bar, said hammer and said bar being under separate control and adapted to engage the rivet on opposite sides 30 of the work, a supply passage conducting pressure fluid to said hammer, a pair of independently operable valves controlling the flow of fluid through said passage, such flow being cut off when either or both of said valves are closed 35 thereby preventing operation of the hammer, means on said hammer for opening one of said valves, and remote control means operated from said bucking bar for opening the other of said valves.

40 2. A riveting assembly, comprising a fluid pressure operated hammer, a bucking bar, said hammer and said bar being carried by separate operators and adapted to engage the rivet on opposite sides of the work, and means placing the operation 45 of said hammer under the joint control of said operators to guard against damage resulting from a premature hammer action, said means comprising a first fluid pressure control valve and means on the hammer for opening said first valve, and a second fluid pressure control valve in series 50 with said first valve and means on the bucking bar for opening said second valve, the means on said bucking bar acting through a flexible cable 55 comprising a sheath attached at one end to said hammer and at the other end to said bar and containing a reciprocable core.

3. A riveting assembly, comprising a fluid pressure operated hammer, a bucking bar, said hammer and said bar being under separate control and adapted to engage the rivet on opposite sides of the work, a supply passage conducting pressure fluid to said hammer, a throttle valve associated with said hammer for controlling the flow of fluid through said supply passage, an auxiliary valve for controlling the flow of fluid through said passage, said valves cooperating to cut off the flow of fluid to said hammer when either or both of said valves are closed, and actuating means for said auxiliary valve in the form of a flexible cable connecting said hammer and said bucking bar, said cable having a longitudinally movable core operable as a plunger from said bucking bar and extending into cooperative relation with said auxiliary valve.

4. A riveting assembly, comprising a fluid pres-

sure operated hammer, a bucking bar, said hammer and said bar being under separate control and adapted to engage the rivet on opposite sides of the work, a supply passage conducting pressure fluid to said hammer, first and second independently operable valves controlling the flow of fluid through said passage, such flow being cut off when either or both of said valves are closed thereby preventing operation of the hammer, first and second manipulative means respectively on said hammer and said bucking bar for opening said valves, and a flexible cable comprising a sheath and a core reciprocable within the sheath connecting said second manipulative means to said second valve and operable to open said valve in response to actuation of said means.

5. A riveting assembly, comprising a fluid pressure operated hammer having a pressure fluid inlet, a throttle valve manipulative from the hammer for controlling the flow of fluid to said hammer, an auxiliary valve for controlling the flow of fluid to said hammer, such flow being cut off when either or both of said valves are closed thereby to prevent operation of said hammer, a housing for said auxiliary valve in the form of a fitting secured in the air inlet of said hammer, said auxiliary valve being movable within said fitting to control the flow of fluid to said inlet, and a flexible cable attached to said fitting and containing a longitudinally movable core in cooperative relation with said valve, said cable extending to a point remote from said hammer where move-

ment of said core may be effected to open said valve, whereby the operation of said hammer may be controlled jointly by the holder of the hammer and someone remote thereto.

10 6. A riveting assembly according to claim 5 and including a bucking bar, said hammer and said bar being under separate control and adapted to engage the rivet on opposite sides of the work, characterized in that said flexible cable interconnects said hammer and said bucking bar and is operable from said bar to open said auxiliary valve.

15 7. A riveting assembly, comprising a fluid pressure operated hammer, a bucking bar, said hammer and said bar being under separate control and adapted to engage the rivet on opposite sides of the work, first and second valves controlling the flow of fluid to said hammer, such flow being cut off when either or both of said valves are closed thereby to prevent operation of said hammer, means on said hammer for opening said first valve, control means on said bucking bar for said second valve, said means having the form of a hand-operated lever, a flexible cable attached 20 at its opposite ends to said hammer and said bucking bar and containing a longitudinally movable core arranged to transmit the movement of said lever to said second valve, said second valve, core and lever being connected for movement as an 25 assembly, and spring means urging said assembly in a direction to close said valve.
